UNITED STATES PATENT OFFICE

152,999

DESIGN FOR A LAMP

Joseph Matas, Berwyn, Pa.

Application October 15, 1947, Serial No. 141,911

Term of patent 7 years

(Cl. D48—20)

To all whom it may concern:

Be it known that I, Joseph Matas, a citizen of the United States, residing in Berwyn, county of Chester, Commonwealth of Pennsylvania, have invented a new, original, and ornamental Design for Lamp, of which the following is a specification, reference being had to the accompanying drawings, which form a part thereof.

I claim:

The ornamental design for a lamp, substantially as shown.

JOSEPH MATAS.
